KILN

Application filed July 3, 1930. Serial No. 485,691.

- My invention relates particularly to a kiln, adapted for heating or roasting generally, but which is particularly applicable to the production of chromates, cement, lime, etc.
- 5 The object of my invention is to provide a kiln of the above character and more particularly an improved construction of kiln hoods having many advantages over the previous constructions of kilns. The object of 10 my invention is especially to provide a cooling zone in the kiln. A further object is to provide a kiln hood which is particularly suited for use on inclined rotary kilns. A kiln made in accordance with my invention may 15 include means for adjusting the angle at which the kiln hood is supported to enable it to be more readily applied to an inclined rotary kiln having a desired angle of inclination.
- 20 A further object is to arrange the kiln hood so that it may be moved readily away from the kiln and to one side thereof, so as to provide free access into the interior of the kiln when desired.
- 25 Further objects of my invention will appear from the detailed description of the same hereinafter.
- While my invention is capable of embodiment in many different forms, for the purpose 30 of illustration I have shown only one form of my invention in the accompanying drawings, in which:
- Fig. 1 is a side elevation of a kiln made in accordance with my invention, shown somewhat diagrammatically;
- 35 Fig. 2 is a side elevation partly in section, showing a kiln made in accordance with my invention;
- Fig. 3 is a transverse section of the same;
- 40 Fig. 4 is a detailed section of the kiln hood supporting device; and
- Fig. 5 is an enlarged longitudinal sectional detail.
- In the drawings I have shown a rotary inclined kiln 1, such as may be used for the 45 roasting of chrome ores in the manufacture of chromates from mixtures of any desired proportions of chrome ore, lime and soda ash, for example. The inclined rotary kiln 1 is supported on two sets of rollers 2 and 3,
- adapted to receive cylindrical tracks 4 and 5 respectively, carried on the outside of the kiln. The kiln may be rotated by means of a gear 6 carried on the outside of the kiln, 55 which may be driven by a gear 7 from any desired source of power. The materials to be treated in the kiln are fed to the upper end of the same through a hopper 8 having a pipe 9 leading therefrom to the interior of the kiln. The lower end of the kiln in the operation thereof is covered by a kiln hood 10 having a refractory lining 11 in such a manner as to fit the end of the kiln which is also provided with a similar refractory lining 12. The kiln hood 10 for this purpose 60 has a central opening 13 in the forward portion thereof in which the lower end of the inclined kiln 1 is adapted to fit, the lower portion of the hood 10 having a discharge opening 14 through which the roasted material 70 containing sodium chromate, calcium chromate and some soda ash, as well as impurities, is adapted to be discharged. The rear face of the hood 10 is provided with a strengthening brace 15 in the form of an 75 I-beam or in any other desired way. Also, through the rear face of the hood 10 there extends a pipe 16 for supplying oil or other fluid fuel which terminates in a spray nozzle 80 17. This oil pipe 16 is located in the center of an air supply pipe 18 provided with a branch pipe 19 having a valve 20 therein to supply the main body of air for burning the fuel and a longitudinally adjustable pipe 21, 85 splined within the pipe 18, in which the oil pipe 16 is mounted, to act as an auxiliary air control moved by a hand-wheel 22 to provide a secondary air control for the burner. As shown in Fig. 2, said air pipe 18 is not only supported from the rear face of the hood 10 but is also supported by means of a web or a bracket 23 upon the interior of a protecting casing 24 made of heat resisting steel such as chrome steel, the rear end of which 90 is secured within the rear face of the hood 10. This protecting casing has at its forward end on the interior thereof a lining of refractory material 25 having an expanding opening 26 therein to provide an injector action on the part of the burning fuel, causing 100

the intake of air into the casing 24 around the burner nozzle and air pipe 18. A further quantity of air enters through the discharge opening 14 into the space around the casing 24, thus providing a cooling zone in which partial oxidation takes place between the hood 10 and the forward end of the casing 24, which extends into the inclined rotary kiln for a distance of about $\frac{1}{8}$ to $\frac{1}{5}$ the 10 length of the kiln. The kiln has a length of about 10 to 18 times the inside diameter thereof.

The kiln hood 10 is, preferably, supported in such a manner as to provide an inclination thereof such as to fit the lower end of the inclined kiln 1 according to the particular angle of the latter. This support is comprised of two longitudinal screws 27 and 28 which are supported against turning when 20 adjusted in place in brackets 29 and 30 respectively on the kiln hood. This is accomplished by providing the screws 27 and 28 with squared heads 31 located in brackets 29 and 30 on the rear face of the hood 10 as 25 shown in Fig. 4, nuts 32 being provided on the other ends of the screws 27 and 28 for tightening them in place. By loosening the nuts 32 the screws 27 and 28 can be moved for the adjustment of screw-threaded sleeves 33 thereon. These sleeves 33 are connected by eyes 34 with suspension rods 35 having screw-threaded thereon turn-buckles 36 which in turn are connected by rods 37 to brackets 38 and 39 which respectively carry 30 wheels 40 and 41 arranged to run upon an I-beam 42 located transversely of the kiln 1. I-beam 42 in turn is arranged to be supported on two longitudinally movable supporting frameworks 43 and 44 for receiving the 40 weight of the hood 10 and its connected supporting mechanism. These frames 43 and 44 are slidably movable longitudinally upon tracks 45 and 46.

In the operation of the apparatus made in accordance with my invention, during the 45 roasting operation within the kiln 1 the hood 10 will be supported in place at the proper angle against the lower end of the kiln as shown in Fig. 2. This angle of inclination 50 is secured by the proper adjustment of the sleeves 33 on the screws 27 and 28 and by the proper elevation secured by the operation of the turn-buckles 36. When it is desired to gain access to the interior of the 55 kiln as for removing any residual materials therein, relining, etc., the kiln hood with the attached parts including the burner, etc., is moved away from the lower end of the kiln 1 by sliding the supporting frames for 60 the I-beam 42 along the tracks 45 and 46 until the inner end of the casing 24 clears the lower end of the kiln 1, after which the hood 10 with attached parts is moved to one side by moving the rollers 40 and 41 along 65 the I-beam 42. The lower end of the kiln

is now entirely open and access may be had thereto unobstructed by the hood 10 and attached parts when any work is desired to be done therein. When the kiln is to be put into operation again, the kiln hood is moved into place again by the reverse series of operations. Whenever desired, a further adjustment of the angle of the hood 10 may be accomplished by adjusting the sleeves 70 75 33 on the screws 27 and 28 and a similar adjustment may be made vertically by means of the turn-buckles 36.

In carrying out the roasting operation in the kiln, I might introduce into the kiln 1, through the hopper 9, a mixture of finely ground chrome ore containing, for instance—

100 parts by weight of chrome ore (containing 50% Cr_2O_3)

70 parts by weight of lime

49 parts by weight of soda ash

In this mixture the lime may, however, vary from 70 parts to 80 parts by weight, and, if desired, the soda ash may vary from 45 parts to 53 parts by weight. Also, the lime may be any other basic refractory material and the soda ash may be substituted with any other alkali carbonate. It will be understood, also, that in this application, whenever I refer to lime or soda ash, such substitute materials may be used if desired. This amount of basic refractory material is at least such as not only to prevent the formation of any undesirable compounds from the soda ash and the silica and the alumina which is contained in the chrome ore but is sufficient also to attain the high yields of chromates hereinafter referred to. Also, the soda ash is present in such quantity to combine with somewhat less than, that is to say about 70% by weight of the chromic oxide present. This mixture is roasted in the kiln at a temperature of about 1000° C. in the oxidizing atmosphere present therein in the upper part of the kiln, that is to say, between the upper end of the burner and the upper end of the kiln after which the materials pass downwardly into the cooling zone, that is to say, between the upper end of the burner and the lower end of the kiln in which the average temperature is approximately 800° C., so that the materials pass out the lower end of the kiln at a temperature of about 600° C. The reactions which take place in the kiln 1 are as follows:

The treatment in the kiln requires approximately 3 hours.

These materials delivered from the kiln 1 are in the form of particles varying in size

from a fine powder to lumps 1 inch in diameter, the latter having been oxidized practically only at the surface thereof, and containing calcium chromate, sodium chromate 5 as well as silicates of lime and alumina. These materials may then be subjected to any desired operations in the usual way for the recovery of the sodium chromate or sodium bichromate therefrom.

10 While I have described my invention above in detail it is to be understood that many changes may be made therein without departing from the spirit of the same as set forth in the claims.

15 I claim:

1. A rotary kiln adapted for roasting chrome ore in the formation of chromates, inclined so as to feed the same forwardly, comprising a source of heat applied at a 20 point therein intermediate the kiln ends, said ends providing, respectively, a roasting zone and a cooling zone and an air conveying housing located around said source of heat.

2. An inclined rotary kiln adapted for 25 roasting chrome ore in the formation of chromates, inclined so as to feed the same forwardly, comprising a source of heat applied at a point therein intermediate the kiln ends, said ends providing, respectively, a 30 roasting zone and a cooling zone and an air conveying housing located around said source of heat.

3. A rotary kiln adapted for roasting chrome ore in the formation of chromates, 35 inclined so as to feed the same forwardly, comprising a source of heat applied at a point therein intermediate the kiln ends, said ends providing, respectively, a roasting zone and a cooling zone, an air conveying 40 housing located around said source of heat and means for supplying heating gases in countercurrent to the ore.

4. A rotary kiln adapted for roasting chrome ore in the formation of chromates, 45 inclined so as to feed the same forwardly, comprising a source of heat applied at a point therein intermediate the kiln ends, said ends providing, respectively, a roasting zone and a cooling zone and an air conveying 50 housing located around said source of heat, the source of heat including a burner located between the roasting and cooling zones.

5. A rotary kiln adapted for roasting chrome ore in the formation of chromates, 55 inclined so as to feed the same forwardly, comprising a source of heat applied at a point therein intermediate the kiln ends, said ends providing, respectively, a roasting zone and a cooling zone, an air conveying housing 60 located around said source of heat, the source of heat including a burner located between the roasting and cooling zones, and means adapted to supply air to the kiln at the discharge end of the cooling zone.

6. An inclined rotary kiln adapted for

roasting chrome ore in the formation of chromates, inclined so as to feed the same forwardly, comprising a source of heat applied at a point therein intermediate the kiln ends, said ends providing, respectively, 70 a roasting zone and a cooling zone and an air conveying housing located around said source of heat, the source of heat including a burner located between the roasting and cooling zones.

7. An inclined rotary kiln adapted for roasting chrome ore in the formation of chromates, inclined so as to feed the same forwardly, comprising a source of heat applied at a point therein intermediate the kiln 75 ends, said ends providing, respectively, a roasting zone and a cooling zone, an air conveying housing located around said source of heat, the source of heat including a burner located between the roasting and cooling zones, and means adapted to supply air to the kiln at the discharge end of the cooling zone.

8. A rotary kiln adapted for roasting chrome ore in the formation of chromates, 80 inclined so as to feed the same forwardly, comprising a source of heat applied at a point therein intermediate the kiln ends, said ends providing, respectively, a roasting zone and a cooling zone and an air conveying housing 85 located around said source of heat, the source of heat including a burner located between the roasting and cooling zones, said burner being arranged to enter the kiln through the cooling zone.

9. A rotary kiln adapted for roasting chrome ore in the formation of chromates, inclined so as to feed the same forwardly, comprising a source of heat applied at a point therein intermediate the kiln ends, said ends providing, respectively, a roasting zone and a cooling zone, an air conveying housing located around said source of heat, the source of heat including a burner located between the roasting and cooling zones, and means 105 adapted to supply air to the kiln at the discharge end of the cooling zone, said burner being arranged to enter the kiln through the cooling zone.

10. A rotary kiln adapted for roasting chrome ore in the formation of chromates, inclined so as to feed the same forwardly, comprising a source of heat applied at a point therein intermediate the kiln ends, said ends providing, respectively, a roasting zone and a cooling zone, and an air conveying 110 housing located around said source of heat, the source of heat including a burner located between the roasting and cooling zones, said burner being arranged to enter the kiln through the cooling zone.

11. A rotary kiln adapted for roasting chrome ore in the formation of chromates, 115

120

125

130

- inclined so as to feed the same forwardly, comprising a source of heat applied at a point therein intermediate the kiln ends, said ends providing, respectively, a roasting zone and a cooling zone, an air conveying housing located around said source of heat, the source of heat including a burner located between the roasting and cooling zones, and means adapted to supply air to the kiln.
12. An inclined rotary kiln having a hood and means for supporting the hood adjustably longitudinally of the kiln, said means including a removable frame provided with a hood suspending means including means for adjustably predetermining the vertical angularity of said hood.
13. An inclined rotary kiln having a hood and means for supporting the hood adjustably longitudinally of the kiln, said means including a removable frame provided with a hood suspending means including means for adjustably predetermining the vertical angularity of said hood, said adjusting means comprising a longitudinal screw having an adjustable sleeve support thereon.
14. An inclined rotary kiln having a hood and vertically adjustable means for supporting the hood adjustable longitudinally of the kiln, said means including a removable frame provided with a hood suspending means including means for adjustably predetermining the vertical angularity of said hood.
